UNITED STATES PATENT OFFICE.

ISADORE BERGER, OF NEWARK, NEW JERSEY, ASSIGNOR TO ELIZABETH H. CHEIN,
OF NEW YORK, N. Y.

TOY BODY FORMED OF SHEET MATERIAL.

Application filed February 8, 1927. Serial No. 168,628.

My invention relates to new and useful improvements in toy elements and more particularly to an element formed from sheet material.

5 An object of my invention is to construct a toy element from sheet material in a novel manner.

Another object is to provide an element from an integral blank which will have several related parts.

10 The invention consists in the improved construction of parts to be more fully described hereinafter and the novelty of which will be particularly pointed out and distinctly claimed.

15 I have fully and clearly illustrated a preferred embodiment of my invention in the accompanying drawings to be taken as a part of this specification, and wherein

20 Figure 1 is a plan view of the blank which has been cut to the desired configuration,

Figure 2 is a side elevation of the completed element when assembled on a chassis, and

25 Figure 3 is a transverse sectional view on the line 3—3 of Figure 2.

Referring to the drawings by characters of reference, the numeral 1 designates a blank of sheet material, preferably sheet 30 metal though cardboard or other board material may be used if desired. The blank 1 includes a hood portion 2, cock-pit or seat portion 3, and a body portion 4.

The hood portion 2 has side members 5, 35 6 which are joined by a center part 7. The side members 5, 6 are provided with fastening members 8, 9 respectively by which the hood portion is fixed on a chassis.

40 The seat portion 3 has side members 10, 11 which are extensions of the sides 5, 6 of the hood portion 2 and which are connected by an intervening part 12. The seat proper 13 is cut from the center part 7 extended but is left integral with the intervening part 45 12 at the back of the seat.

Each of the sides 10, 11 of the seat portion 3 has an end section 14, 15 respectively which connects the seat portion to the body portion 4. The side members of the body 50 portion 4 are identical and therefore but one will be described. The side member 16 has a lower part 17 which is joined to a longitudinal panel 18 by a horizontal strip 19 and a top part 20 which is joined to the 55 panel 18 by a horizontal strip 21. The edge

of the top part 20 is finished off by a flange 22 and the edge of the lower part 17 has a supporting flange 23. Suitable lugs 24 are provided on the body portion 4 to fasten it to a back (not shown) carried by the chassis. 60

The toy element is formed as follows: The upper and lower parts 20 and 17 are bent downwardly from the plane of the drawing into parallel planes at right angles to the panel 18 along lines 30. The side 65 members then have the upper and lower parts bent outwardly respectively from each other to lie in a common plane parallel to panel 18. The flanges 22 and 23 are then bent upwardly and downwardly respectively 70 at right angles to the plane of the panel. The whole side member is then bent upwardly along line 40 and back along line 41 so that the end section 14 is at right angles to seat side 5 and side member 16 is parallel 75 to side 5. Both of the side members of the body portion are formed as just described. The seat portion 13 is now bent down along line 50 to form an obtuse angle with the intervening part 12 to make the back 51 and 80 the seat proper 13 is then bent upwardly to make a right angle with back 51. The rear edge 52 of the intervening part 12 is then bent upwardly along line 53 to form the front of the body portion 4. Finally the 85 sides 5, 6 are bent downwardly at right angles to the plane of the drawing into parallel planes along lines 60, 61 which will also bring the sides 16, 16 of the body 4 into parallel planes, and the center part 7 is 90 bowed slightly upward.

The completed element may then be placed upon a chassis 70, Figure 2, and secured thereon by the lugs 8, 9.

Having thus described my invention what 95 I claim and desire to secure by Letters Patent of the United States is:

1. A toy body comprising a single blank 100 of sheet material having a hood portion, a seat portion and a body portion, said body portion having side members with outwardly projecting panels, and an end section closing the end of each said panel and connecting said body portion to said seat portion.

2. A toy body, comprising a single blank 105 of sheet material having a hood portion, a seat portion and a body portion, said hood portion having side members in two substantially parallel planes, said seat portion having side members in two substantially 110

parallel planes, the side members of said hood portion and the side members of said seat portion lying in the same two parallel planes, said body portion having side members with outwardly projecting oppositely disposed panels, and an end section closing the end of each said panel and connecting said body portion to said seat portion.

3. A toy body comprising a single sheet of material having a hood portion, a seat portion and a body portion, said hood portion comprising a top section and down-

wardly bent side sections, a part of the said top section being cut out and bent to form the seat portion, said body portion comprising two plates having longitudinally disposed outwardly bent panels and bent over flanges, and integral end sections for said panels intermediate the sides of the hood portion and the end of the panels of the body sections. 15

In testimony whereof ISADORE BERGER has signed his name to this specification, this 31st day of January, 1927.

ISADORE BERGER.
